TELEVISION SYNCHRONIZING SYSTEM

Harold M. Lewis, Great Neck, N. Y., assignor to
Hazeltine Corporation, a corporation of Delaware

Application April 29, 1938, Serial No. 204,956

12 Claims. (Cl. 178—6.8)

This invention relates to television systems and more particularly to synchronizing apparatus for such systems. The invention is especially concerned with the development of an improved synchronizing signal.

In accordance with present television practice, there is developed and transmitted a signal which comprises a carrier wave modulated during successive intervals or trace periods by video-frequency components representative of the light and shade values of an image being transmitted. During retrace intervals between the trace periods, the carrier wave is modulated by synchronizing impulses or components which correspond to the initiations of successive lines and fields in the scanning of the image. At the receiver, a beam is developed and so deflected as to scan and illuminate a target in a series of parallel lines or fields. The video-frequency components of the received signal are utilized to control the intensity of the beam. The line- and field-scanning synchronizing components are separated from the video-frequency components and from each other and utilized to synchronize the operation of the receiver scanning apparatus with the similar scanning apparatus utilized at the transmitter in developing the signal. The transmitted image is thereby reconstructed on the target of the receiver.

In scanning of the interlaced type, the line-scanning and field-scanning frequencies are so related that successive fields are staggered, the lines of one field falling between or interlacing those of a preceding field, and, due to persistence of vision, the optical effect produced is as though each frame or group of fields comprised a multiple of the actual number of lines scanned per field and the frame-scanning frequency equalled the field-scanning frequency.

Various types of carrier-signal modulation, scanning, and synchronizing methods and apparatus heretofore have been proposed. The type of synchronizing signal required ordinarily depends in part upon the type of carrier signal employed and the type of scanning utilized. For example, in certain systems negative modulation is employed; that is, a decrease in carrier amplitude corresponds to an increase in illumination; while in other systems positive modulation is utilized, in which an increase in carrier amplitude corresponds to an increase in illumination. The synchronizing components of the signals used in these systems ordinarily have amplitude values outside of the range of the video-frequency components, being represented by increases in carrier

amplitude where negative modulation is employed and by decreases in carrier amplitude where positive modulation is employed.

In interlaced scanning systems, certain of the field-synchronizing impulses must be initiated between successive line-synchronizing impulses. In order that the line- and field-synchronizing impulses may be successfully separated from the video-frequency components and from each other for utilization, various types of synchronizing signals and separating apparatus have been proposed. More particularly, the line-synchronizing impulses have been given a certain critical wave form characteristic while the field-synchronizing impulses have been given a critical wave form characteristic which corresponds to, but is different from, that of the line-synchronizing impulses. Suitable means are provided at the receivers which are responsive to these critical characteristics for separating the field-synchronizing impulses from the line-synchronizing impulses.

In various systems of the prior art, synchronizing signals have been utilized in which the field-synchronizing impulses have amplitudes, durations, or shapes which are different from the corresponding characteristics, that is, the amplitudes, durations, or shapes, respectively, of the line-synchronizing impulses. In the first case, amplitude-discriminating circuits are employed as the separating apparatus at the receivers; in the second case, duration-responsive circuits, such as integrating or time constant networks, are utilized; while in the third case, differentiating circuits are generally employed.

Thus, in order to utilize synchronizing signals from a given transmitter, a receiver must include the particular type of synchronizing apparatus responsive to the particular critical characteristic of the synchronizing signal utilized by such transmitter. That is, a given receiver has been capable of reproducing the programs of only such stations as transmit synchronizing signals of the particular type for which it is designed. Obviously, this materially limits the use of a receiver, since the various stations within a given range of reception may transmit synchronizing signals of different types.

It is an object, therefore, of the present invention to provide a television system including a synchronizing-signal-generating apparatus capable of developing and transmitting an improved synchronizing signal which is utilized by receivers including synchronizing-signal-separating apparatus designed to respond to synchronizing signals

having critical wave form characteristics of various types.

In accordance with the invention, a television broadcasting system comprises a plurality of receivers, certain of which comprise synchronizing-signal separating apparatus designed to respond to synchronizing signals having individual critical wave form characteristics of different types, together with a television transmitter synchronizing-signal generator including means for developing line-synchronizing impulses, each having a plurality of predetermined critical wave form characteristics. Means are also provided in the generator for developing field-synchronizing impulses, each having a plurality of predetermined critical wave form characteristics, corresponding to, but different from, those of the line-synchronizing impulses, together with means for combining the developed line-synchronizing and field-synchronizing impulses with like polarity to develop and transmit a composite synchronizing signal to synchronize all of said certain receivers.

For a better understanding of the invention, together with other and further objects thereof, reference is had to the following description, taken in connection with the accompanying drawings, and its scope will be pointed out in the appended claims.

In the accompanying drawings, Fig. 1 is a schematic circuit diagram of a complete television transmitting apparatus embodying the invention; and Fig. 2 is a group of curves illustrating the wave forms of various synchronizing signals to aid in the understanding of the invention.

Referring now more particularly to Fig. 1 of the drawings, there is illustrated a television transmitting system comprising a signal generator 10, which may be of a conventional design including the usual cathode-ray signal generating tube and scanning elements. For developing scanning voltages or currents for the generator 10, there are provided a line-frequency saw-tooth wave generator 11 and a field-frequency saw-tooth wave generator 12, the output circuits of these generators being connected to the scanning elements of the signal generator 10 in the conventional manner. In order to block out the cathode ray of the generator 10 during the retract scanning periods, there is provided a block-out wave generator 13 having its output circuit suitably connected to the signal generator 10. For providing impulses to suppress undesirable signal impulses during retrace scanning periods and to ensure proper form of the modulation signal to be developed, there is provided a pedestal impulse generator 14 and, in order to develop a scanning synchronizing signal in accordance with the present invention, there is provided synchronizing-signal-generating apparatus indicated generally at 15 and hereinafter more fully described.

For the purpose of synchronizing the generators 11-14, inclusive, and the apparatus 15, there is provided a timing impulse generator 16 coupled to the input circuits of the generators 11-14, inclusive, and apparatus 15. The timing impulse generator 16 is preferably stabilized by means of a connection 17 to a suitable source of periodic voltage, for example, to the power supply circuit or to the synchronizing voltage source of a motion picture mechanism, where such is employed.

Connected in cascade to the output circuit of the signal generator 10, in the order named, are video-frequency amplifiers 18, 19 and 20, a modulator 21 and associated coupled carrier-frequency oscillator 22, a power amplifier 23, and an antenna

system 24, 25, all according to conventional practice. The output circuit of the pedestal generator 14 is coupled to the video-frequency amplifier 19, while the output circuit of the synchronizing-signal-generating apparatus 15 is coupled to the 5 video-frequency amplifier 20.

Neglecting for the moment the details of the synchronizing-signal-generating apparatus 15, the system just described comprises the elements of a television transmitting system of conventional 10 design and, the various parts thereof being of any well-known construction, a detailed description of the general system and its operation is unnecessary. Briefly, however, the image of a scene to be transmitted is focused on the target of a cathode-ray tube of the signal generator 10, in which tube a cathode ray is developed, focused and accelerated toward the target in the usual manner. Scanning or deflecting currents or voltages developed by the generators 11 and 12 are applied 20 to the scanning elements of the generator 10 to provide electric fields which serve to deflect the cathode ray horizontally and vertically, thereby to scan successive series of parallel lines, or fields, upon the target. The deflecting currents or voltages, and hence the scanning fields, are of well-known saw-tooth wave form, providing a relatively slow linear trace and rapid retrace. The number of lines per field is determined by the relative values of line-scanning and field-scanning frequencies. The line-scanning frequency is preferably a fractional multiple of the field-scanning frequency so that the successive fields of parallel lines traced on the target are interlaced in the well-known manner. The line-scanning and 30 frame-scanning frequencies may, for example, be 13,230 and 60 cycles per second, respectively.

Block-out impulses developed by the generator 13 are applied to the control electrode of the cathode-ray tube to suppress or block out the beam during retrace portions of the scanning cycles, while pedestal impulses developed by the generator 14 are applied to the amplifier 19 to modify the shape of the resultant video-frequency wave developed to aid in separating the line-synchronizing and frame-synchronizing impulses at the receiver. The synchronizing-impulse signal developed by the apparatus 15 is applied to the modulation amplifier 20 while the timing impulses developed by the generator 16 are applied to the generators 11-14, inclusive, and the apparatus 15 to lock these generators and apparatus in synchronization.

The photosensitive elements of the target in the cathode-ray tube of the generator 14 being 55 electrically affected to an extent dependent upon the varying values of light and shade at the corresponding incremental areas of the image focused thereon, as the cathode ray scans the target, a video-frequency voltage of correspondingly varying amplitude is developed in the output circuit of the generator 10 and applied to the video-frequency amplifier 18, wherein this voltage is amplified and from which it is translated to the amplifier 19. Here the video-frequency voltage 60 is further amplified and mixed with pedestal impulses supplied from the generator 14. The amplified and mixed voltages in the output circuit of the amplifier 19 are thereupon applied to the amplifier 20, wherein they are further amplified 70 and mixed with the synchronizing-impulse signal supplied from the apparatus 15. The modulation voltages are thereupon supplied to the modulator 21, wherein they are so impressed upon the carrier wave generated by the oscillator 22 as to develop 75

a modulated carrier, preferably a positively modulated signal such as described above. The resultant modulated-carrier signal is delivered to the power amplifier 23 for amplification and is thereafter impressed upon the antenna system 24, 5 25 to be broadcast.

Referring now more particularly to the apparatus 15 embodying the present invention, for the purpose of developing line-synchronizing impulses of the proper frequency and wave form characteristics, there is provided a generator 26 which may comprise apparatus of any suitable type adapted to develop periodic impulses of line-scanning frequency, for example, 13,230 cycles per 10 second, and of rectangular-peaked-impulse wave form, as indicated by the curve immediately above the generator 26. The input circuit of this generator is coupled to the timing generator 16 for synchronization, while its output circuit is 15 coupled to a limiter and amplifier 27 which may comprise a suitable conventional circuit arrangement including, for example, vacuum tubes so biased as to cut off predetermined portions of the applied waves, for example, the portion shown 20 above and below the broken lines on the curve above the generator 26.

For the purpose of developing alternate periodic impulses of the same frequency and wave form as the line-synchronizing impulses but displaced 30 180 degrees with respect thereto, that is, occurring between the line-synchronizing impulses, a generator 28 and a limiter and amplifier 29 are provided which may be of the same design as the stages 26 and 27, respectively. The generator 28 35 is also coupled to the timing impulse generator 16 to receive synchronizing impulses therefrom.

In order to develop periodic rectangular impulses for use as field-synchronizing impulses, there is provided a periodic wave generator 30, 40 which may comprise any suitable conventional oscillator circuit adapted to develop a wave of double the line-scanning frequency, for example 26,460 cycles, and of substantially rectangular-impulse wave form, such as illustrated by the 45 curve immediately above the generator 30. Such an oscillator circuit is described in detail in Patent 2,226,706 issued Dec. 31, 1940 to Madison Cawein for Television scanning system to which reference may be had for details of construction. 50 The input circuit of this generator is coupled to the timing generator 16 for synchronization thereby at the required frequency. It will be noted that the impulses of the last-mentioned wave initiate at the same time as the line-synchronizing 55 impulses and alternate line impulses developed by the generators 19 and 20 and, if desired, the several generators may be suitably locked together to maintain these relations. These relations are correct for the purpose of developing the final 60 composite synchronizing wave, as will be apparent from the description of the general operation of the system hereinafter set forth.

A combining network 31 is included in the generator 15 and comprises a line-synchronizing impulse amplifier 32, an alternate-impulse amplifier 33 and a field-synchronizing impulse amplifier 34, having their input circuits connected to the output circuits of the limiters and amplifiers 27 and 29 and the generator 30, respectively, as shown. The 65 70 output circuits of the amplifiers 32, 33 and 34 are connected in parallel and coupled to a final limiter 35, whose output circuit is in turn connected to the video-frequency amplifier 20 for supplying the composite synchronizing signal developed by the 75 generator 15.

For the purpose of controlling the operation of the combining network 31 there are provided delay and duration control circuits, including field-frequency generators 36 and 37 designed to develop periodic impulse waves of rectangular wave form, such as are illustrated immediately above the generators 36 and 37, and of field frequency, for example, 60 cycles. The timing impulse generator 16 is designed to develop in one of its output circuits a periodic voltage wave of this 60-cycle frequency which may be of the wave form illustrated at the left of the generators 36 and 37 and this output circuit is connected to the input circuits of the generators 36 and 37 for synchronizing the same. 10 15

The timing impulses from timer 16 occur at the initiation of the field retrace scanning periods. The rectangular impulses developed by the generators 36 and 37 are of predetermined durations which are the determining factors in the delays 20 to be obtained. Differentiating circuits 38 and 39 are connected to the output circuit of the generators 36 and 37, respectively, and may comprise any suitable conventional voltage-differentiating circuit arrangements for differentiating the rectangular-impulse waves developed by the generators 36 and 37 to derive therefrom double-impulse waves, such as shown immediately above the elements 38 and 39. The positive and negative peaks 25 of these waves occur simultaneously with the leading and trailing edges, respectively, of their corresponding rectangular impulses. Duration control circuits 40 and 41, which may, for example, be conventional relaxation oscillators, are connected to the delay circuits 38 and 39, respectively, for developing periodic-impulse waves 30 which are preferably of rectangular wave form, as shown above, and of the same frequency as the wave derived from the timing generator. The circuits 40 and 41 are so coupled to the circuits 38 40 and 39 as to be synchronized by the negative, or second, peaks of each of their respective double impulses; that is, the impulses of the outputs of units 40 and 41 are initiated upon the occurrence 45 of the second or negative peaks of their respective double impulses. The periodic impulse outputs of units 40 and 41, therefore, are delayed in phase with respect to the impulses developed by the timing generator 16 by an amount equal to the duration of the rectangular impulses developed by the 50 generators 36 and 37 and are of different predetermined durations, as determined by the duration control circuits 40 and 41. For a detailed description of circuits suitable for the stages 36, 38, 40 and 31, 39, 41, reference may be had to the 55 above-mentioned Patent 2,226,706, which discloses the details of a similar circuit arrangement.

The impulse voltage outputs of the generators 40 and 41 are applied to the amplifiers 33 and 34, respectively, of the combining network to control the operation of these amplifiers. Preferably, the amplifiers 33 and 34 are normally biased beyond cutoff so that the signals applied thereto from the amplifiers 29 and 30 are not 60 passed thereby, and the control impulses are applied positively from the circuits 40 and 41 so as to unblock the amplifiers 33 and 34, respectively, for periods of predetermined duration, delayed with respect to the original 60-cycle 70 impulses developed by the timing generator 16, by predetermined amounts, and occurring at the field frequency.

The general operation of the system may best be explained with reference to the curves of 75

Fig. 2. The curves A, B, C and D illustrate the wave forms of four different composite line- and field-synchronizing impulse signals, such as have heretofore been individually employed in various systems of the prior art. In each case, the line-synchronizing impulses have a single predetermined critical wave form characteristic while the field-synchronizing impulses have a single predetermined critical wave form characteristic which corresponds to, but is different from, that of the line-synchronizing impulses. It is by virtue of this difference in wave form characteristic that synchronizing-separating apparatus of a receiver designed to respond to the particular type of synchronizing signal is able to separate the field-synchronizing impulses from the line-synchronizing impulses prior to utilizing them for synchronizing its scanning wave-generating apparatus. In other words, such synchronizing-signal-separating apparatus is generally designed to be responsive only to the particular distinguishing wave form characteristic of a particular type of synchronizing signal and, hence, such a wave form characteristic is referred to herein and in the appended claims as critical.

In curve A, the critical wave form characteristic of the synchronizing impulses is their amplitude, the field-synchronizing impulses, as indicated at *f*, being of substantially greater amplitude than the line-synchronizing impulses indicated at *l*. The separating apparatus for such a synchronizing signal need comprise only a limiting or amplitude-responsive device, for example, a diode to which the combined signal is applied negatively, and the anode of which is initially so biased as to render the tube conductive only during the occurrence of the field-synchronizing impulses. The result of such arrangement is that only the field-synchronizing impulses are repeated in the output circuit of the device. Such an arrangement is described in detail in copending application Serial No. 177,663, filed December 2, 1937 by Harold M. Lewis, for Television scanning systems, to which reference may be had for details of construction.

The critical wave form characteristic of the impulses of curve B is their duration, the field-synchronizing impulses *f* being of substantially greater duration than the line-synchronizing impulses *l*. For this type of synchronizing signal, the separation apparatus has generally comprised a duration-responsive, or time-constant, device which develops a signal having impulses with amplitude proportional to the durations of the impulses of the composite synchronizing signal. The impulses of different amplitudes may then be readily separated by a suitable limiting device, as explained above. For details of construction of a suitable duration-responsive device, reference may also be had to copending application Serial No. 177,679, filed December 2, 1937 by A. V. Loughren, for Television scanning systems.

Curve C is somewhat similar to curve B in that the field-synchronizing impulses *f* differ from the line-synchronizing impulses *l* by being of greater duration. The effective field-synchronizing impulses of this signal may be considered as having a duration such as indicated at *g*. This impulse is of the serrated type however; that is, portions of the impulse are in effect cut away to permit the uninterrupted recurrence of the line-synchronizing impulses. The separation of the field-synchronizing impulses from the line-synchronizing impulses in this case is generally accomplished by time-constant circuits of the integrat-

ing type. In order that such circuits shall not be undesirably affected by the fact that the phase of succeeding field-synchronizing impulses relative to their respective preceding line-synchronizing impulses is different in interlaced scanning systems, for which such signals are generally employed, a special separating arrangement must be resorted to. More particularly, for predetermined periods indicated at *h*, initiating prior to the occurrence of the serrated field-synchronizing impulses, the line-frequency impulses are doubled, as by the addition of alternate impulses inserted in the composite signal. Since this impulse doubling is initiated just prior to the occurrence of each field-synchronizing impulse, the integrating apparatus is always in substantially the same condition at the commencement of all field-synchronizing impulses, regardless of the variations in the phase displacement of alternate field-synchronizing impulses from their respective preceding line-synchronizing impulses which are inherent in interlaced scanning systems. For details of construction of a suitable integrating device for separating the field- from the line-synchronizing impulses of this type of signal, reference may be had to British Patent No. 423,685, dated November 3, 1933.

Curve D illustrates a composite synchronizing signal in which the critical characteristic of the impulses is their shape. More particularly, this wave includes line-synchronizing impulses which have leading edges of steeper slope than their trailing edges and field-synchronizing impulses which have trailing edges of relatively steeper slope than their leading edges. In order to separate the field-synchronizing impulses from the line-synchronizing impulses of this type of signal, the synchronizing apparatus at the receiver comprises devices which are responsive to the shape or, more particularly, to the slope of the leading and trailing edges of the synchronizing impulses. For example, devices may be employed which differentiate the composite signal to derive a synchronizing signal in which line-synchronizing and field-synchronizing impulses are poled in opposite senses. Hence, by applying this derived signal with the proper polarity to the scanning wave generator independently of the field-synchronizing impulses will effect synchronization of the field-scanning wave generator independently of the line-synchronizing impulses. In copending application Serial No. 177,663, above referred to, apparatus suitable for effecting separation of the line- and field-synchronizing impulses of this type of signal is described in detail and reference may be had thereto for details of construction.

It will be understood that, in each of the cases just described, generally the composite wave is differentiated and the line-scanning generator is then excited by the resultant differentiated line-synchronizing components so that the field components do not interfere with the normal operation of the line-scanning apparatus. In certain cases, however, such as that represented by curve D, distinctive derived line-synchronizing impulses are developed and they may be used for synchronization.

The purpose and general results obtained by using the system of the present invention may be more clearly explained by reference to the other curves of Fig. 2.

In Fig. 2, curve E illustrates the wave form of the modulation signal developed by the transmitting system of Fig. 1 including the synchro-

nizing signal-generating apparatus of the present invention. The portion of the curve indicated at x represents a field retrace interval. The letters w , b , and s represent the respective 5 signal levels corresponding to white, black, and the peak amplitude of the synchronizing impulses in the black direction. If this signal, as shown, is applied to the carrier wave with proper polarity as modulation, it will be apparent that 10 increases in amplitude of the carrier correspond to increases in illumination of the image, while the synchronizing impulses are all represented by decreases in carrier amplitude. Such a signal is generally termed a positively modulated 15 signal.

In the operation of the generating apparatus 15, the generators 26 and 28, synchronized by the timing generator 16, serve to develop periodic 20 rectangular or peaked-impulse waves of line-scanning frequency but with the impulses developed by the generator 28 occurring 180 degrees out of phase with respect to, or midway between, the impulses developed by the generator 26. These waves are delivered to the limiters and 25 amplifiers 27 and 29, respectively, wherein, by virtue of the limiting and amplifying action, as has been explained, there are developed signals comprising periodic impulses having leading edges of steeper slope than their trailing edges. 30 The latter signals are thereupon impressed upon the input circuits of the amplifiers 32 and 33 of the combining network 31. The line-synchronizing and alternate impulses are indicated at l and a in the composite signal illustrated by curve E 35 of Fig. 2.

The generator 30 serves to develop a periodic wave comprising impulses of substantially rectangular wave form, occurring at double the line frequency and initiating with the alternate and 40 line-synchronizing impulses developed in the output circuits of the limiters and amplifiers 27 and 29. This rectangular-impulse wave is impressed upon the input circuit of the amplifier 34. Certain of these rectangular impulses, which 45 serve as the field-synchronizing impulses, are indicated at f on curve E .

The timing impulse generator 16 also develops 50 in one of its output circuits a periodic wave comprising impulses at the field frequency, 60 cycles in the present case, which occur at the initiation of the field retrace periods, one of which is indicated at x in the curve E of Fig. 2. The generators 36 and 37, synchronized by these field-frequency impulses, develop periodic waves 55 having impulses of rectangular wave form initiating with the timing impulses from timer 16 and of durations corresponding to the delay periods d_1 and d_2 , respectively, indicated in curve E ; that is, delayed for predetermined periods 60 with respect to the initiation of the field retrace periods.

These rectangular-impulse waves are differentiated by the circuits 38 and 39 to derive the double-impulse waves having the second pulse of 65 each double impulse occurring at the trailing edges of the last-mentioned rectangular impulses. The second pulses of the double impulses are utilized to synchronize the duration control circuits 40 and 41 so that periodic waves are developed therein having impulses of rectangular wave form, initiating with the occurrence of the second pulses of the double impulses and of predetermined different durations. The durations 70 of the impulses developed by the circuit 40 correspond to the period y indicated on curve E

while the duration of the impulses developed by the circuit 41 corresponds to the similarly indicated period z .

As explained above, the control impulses developed by the circuits 40 and 41 are applied positively to the amplifiers 33 and 34, which amplifiers are normally biased beyond cutoff, so as to unblock these amplifiers and permit the alternate impulses occurring between the line-synchronizing impulses to be combined with the 10 line-synchronizing impulses during the periods y occurring at the field-scanning frequency and the rectangular field-synchronizing impulses to be combined with like polarity with the line-synchronizing and alternate impulses during the periods z occurring during, but of lesser duration than, the periods y , the composite signal, including the three different types of impulses, being developed in the output circuit of the combining network and applied to the limiter 35. This lim- 15 iter serves to remove peak pulses corresponding to line-synchronizing and alternate impulses which are superimposed on the rectangular impulses in the signal developed in the output circuit of the network 31, as shown in dotted lines 20 on curve E , so that the composite synchronizing signal developed in the output circuit of the limiter 37 is of the form illustrated by the solid line portion x of curve E of Fig. 2. It will be seen that the line-synchronizing impulses and the field- 25 synchronizing impulses of the composite synchronizing signal of Curve E have the different distinguishing wave form characteristics of those of Curves A-D inclusive; that is, they are of different amplitudes, different durations, and have 30 leading and trailing edges of different slopes so that the impulses are of different shapes. This complete synchronizing signal, as explained above, is translated to the amplifier 20 wherein it is amplified and mixed with the video-modulation frequencies to develop the complete modulation wave, the envelope of which is illustrated by Curve E . This complete wave is thereupon 35 impressed as modulation on the carrier wave in the modulator 21 and the modulated carrier wave is amplified in the power amplifier 23 and then broadcast.

Referring now to curves F-I, these curves serve to illustrate how the synchronizing signal of the present invention, as illustrated by curve 50 E , is adapted for use by receivers having the various different types of synchronizing apparatus briefly described above; that is, adapted for utilizing a particular one of synchronizing-signal components illustrated by the curves A-D, 55 inclusive.

Consider first a receiver having synchronizing-signal-separating apparatus designed for a signal such as illustrated by curve A, that is, apparatus responsive to a signal in which the difference in amplitude is the critical wave form characteristic. It will be clear that the line-synchronizing and field-synchronizing impulses of the composite synchronizing signal of the present invention have this characteristic so that, if this signal is received by the receiver under consideration, its limiting device will operate as described above in connection with the curve A to derive from the composite synchronizing signal a field-synchronizing signal such as illustrated by 60 curve F .

Second, consider a receiver having synchronizing-signal-separating apparatus designed to utilize a signal such as illustrated by curve B, 75

that is, responsive to a signal in which the difference in duration is the critical wave form characteristic. Since the signal of the present invention also has this characteristic, if such signal is received by the second receiver, its synchronizing-signal-separating apparatus will operate, as described above in connection with curve B, in response to the differences in durations of the line-synchronizing and field-synchronizing impulses, to develop a signal such as is illustrated by curve G and this derived signal may then, if desired, be applied to a limiting device to remove the line-synchronizing impulses.

Again, consider a third receiver having synchronizing-signal-separating apparatus designed to utilize a signal such as illustrated by curve C, having field-synchronizing impulses of greater duration than the line-synchronizing impulses, with alternate impulses inserted during part of the field retrace period. Here again, the composite synchronizing signal of the present invention includes the same critical characteristic as the signal C. It includes field-synchronizing impulses of relatively long duration as well as additional alternate impulses. When received by the third receiver, therefore, the signal of the present invention will be applied to integrating circuits of its synchronizing-signal separator, as described above in connection with curve C, and a field-synchronizing signal such as is illustrated by curve H is developed thereby. This derived signal may then be utilized in the conventional manner to synchronize the field-scanning apparatus independently of the line-synchronizing impulses, by virtue of the greater amplitude of the portion of the wave of curve H corresponding to the field-synchronizing impulses of the signal of curve E.

Finally, consider a fourth receiver which is designed to utilize a synchronizing signal such as is illustrated by curve D; that is, one in which the critical wave form characteristic is the shape, specifically the relative steepness, of the leading and trailing edges of the line- and field-synchronizing impulses. Here again, it will be apparent that the synchronizing signal of the present invention includes the particular critical wave form characteristics in question. That is, the leading edges of the line-synchronizing impulses are relatively steep compared to their trailing edges, while both the trailing and leading edges of the field-synchronizing impulses are relatively steep compared to trailing edges of the line-synchronizing impulses. In this case, therefore, when the composite synchronizing signal of the present invention is received by the fourth receiver, it is applied to the differentiating device of the synchronizing-signal-separating apparatus and a signal is derived thereby having a wave form such as is illustrated by curve I. As explained above in connection with curve D, by applying the derived synchronizing signal with proper polarity, the field-scanning generator may be synchronized independently of the line-synchronizing impulses.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

75 What is claimed is:

1. A television broadcasting system comprising, a plurality of receivers, certain of which comprise synchronizing-signal separating apparatus designed to respond to synchronizing signals having individual critical wave form characteristics of different types, a television transmitter synchronizing-signal generator including means for developing line-synchronizing impulses each having a plurality of predetermined critical wave form characteristics, means for developing field-synchronizing impulses each having a plurality of predetermined critical wave form characteristics corresponding to but different from those of said line-synchronizing impulses, and means for combining said line-synchronizing and field-synchronizing impulses with like polarity to develop and transmit a composite synchronizing signal to synchronize all of said certain receivers. 10 15

2. A television broadcasting system comprising, a plurality of receivers, certain of which comprise synchronizing-signal separating apparatus designed to respond to synchronizing signals having individual critical wave form characteristics of different types, a television transmitter synchronizing-signal generator including means for developing line-synchronizing impulses each having a predetermined amplitude and duration, means for developing field-synchronizing impulses each having a predetermined amplitude and duration different from the corresponding characteristics of said line-synchronizing impulses, and means for combining said line-synchronizing and field-synchronizing impulses with like polarity to develop and transmit a composite synchronizing signal to synchronize all of said certain receivers. 20 25 30 35

3. A television broadcasting system comprising, a plurality of receivers, certain of which comprise synchronizing-signal separating apparatus designed to respond to synchronizing signals having individual critical wave form characteristics of different types, a television transmitter synchronizing-signal generator including means for developing line-synchronizing impulses of a first predetermined frequency, each having a predetermined amplitude and duration, means for developing other impulses of double said predetermined frequency, each having a predetermined amplitude and duration different from the corresponding characteristics of said line-synchronizing impulses, means for developing alternate impulses at said predetermined frequency and occurring between said line-synchronizing impulses, means for combining said line-synchronizing and said alternate impulses during predetermined periods occurring at a predetermined field-scanning frequency, and means for combining said other impulses with said line-synchronizing and alternate impulses during predetermined periods occurring during, but of less duration than, said first named periods and for transmitting the resultant signal to synchronize all of said certain receivers. 40 45 50 55 60

4. A television broadcasting system comprising, a plurality of receivers, certain of which comprise synchronizing-signal separating apparatus designed to respond to synchronizing signals having individual critical wave form characteristics of different types, a television transmitter synchronizing-signal generator including means for developing line-synchronizing impulses, each having a predetermined amplitude and shape, means for developing field synchronizing impulses, each having a predetermined 65 70 75

amplitude and shape different from the corresponding characteristics of said line-synchronizing impulses, and means for combining said line-synchronizing and field-synchronizing impulses with like polarity to develop and transmit a composite synchronizing signal to synchronize all of said certain receivers.

5. A television broadcasting system comprising, a plurality of receivers, certain of which comprise synchronizing-signal separating apparatus designed to respond to synchronizing signals having individual critical wave form characteristics of different types, a television transmitter synchronizing-signal generator including 10 means for developing line-synchronizing impulses each having a predetermined amplitude, shape and duration, means for developing field-synchronizing impulses, each having a predetermined amplitude, shape and duration different 15 from the corresponding characteristics of said line-synchronizing impulses, and means for combining said line-synchronizing and field-synchronizing impulses with like polarity to develop and transmit a composite synchronizing signal to synchronize all of said certain receivers.

6. A television broadcasting system comprising, a plurality of receivers, certain of which comprise synchronizing-signal separating apparatus designed to respond to synchronizing signals having individual critical wave form characteristics of different types, a television transmitter synchronizing-signal generator including means for developing line-synchronizing impulses of a first predetermined frequency, each 20 having a predetermined shape, amplitude and duration, means for developing field-synchronizing impulses of double said predetermined frequency, each having a predetermined amplitude, shape and duration different from those of said 25 line-synchronizing impulses, means for developing alternate impulses at said predetermined frequency occurring between said line-synchronizing impulses, means for combining said line-synchronizing and said alternate impulses during predetermined periods occurring at a predetermined field-scanning frequency, and means for combining said field-synchronizing impulses with said line-synchronizing and alternate impulses during predetermined periods occurring during, but of less duration than, said first-named periods and for transmitting the resultant signal to synchronize said certain receivers.

7. A television broadcasting system comprising, a plurality of receivers, certain of which comprise synchronizing-signal separating apparatus designed to respond to synchronizing signals having individual critical wave form characteristics of different types, a television transmitter synchronizing-signal generator including means for developing line-synchronizing impulses each having a predetermined duration and shape, means for developing field-synchronizing impulses, each having a predetermined duration and shape different from the corresponding characteristics of said line-synchronizing impulses, and means for combining said line-synchronizing and field-synchronizing impulses to develop and transmit a composite synchronizing signal to synchronize all of said certain receivers.

8. A television broadcasting system comprising, a plurality of receivers, certain of which comprise synchronizing-signal separating apparatus designed to respond to synchronizing signals having individual critical wave form characteristics of different types, a television trans-

mitter synchronizing-signal generator including means for developing line-synchronizing impulses of a first predetermined frequency, each having a predetermined shape and duration, means for developing field-synchronizing impulses of double said predetermined frequency, each having a predetermined shape and duration different from the corresponding characteristics of said line-synchronizing impulses, means for developing alternate impulses at said predetermined frequency occurring between said line-synchronizing impulses, and means for combining said line-synchronizing and said alternate impulses during predetermined periods occurring at a predetermined field-scanning frequency, and means for combining said field-synchronizing impulses with said line-synchronizing and alternate impulses during predetermined periods occurring during, but of less duration than, said first-named periods and for transmitting the resultant signal to synchronize said certain receivers.

9. A television broadcasting system comprising, a plurality of receivers, certain of which comprise synchronizing-signal separating apparatus designed to respond to synchronizing signals having individual critical wave form characteristics of different types, a television transmitter synchronizing-signal generator including means for developing line-synchronizing impulses of predetermined duration, each having an edge of a predetermined slope, means for developing field-synchronizing impulses, each having a different duration from said line-synchronizing impulses and having an edge corresponding to said edges of said line-synchronizing impulses of a predetermined different slope, and means for combining said line-synchronizing and field-synchronizing impulses with like polarity to develop and transmit a composite synchronizing signal to synchronize all of said certain receivers.

10. A television broadcasting system comprising, a plurality of receivers, certain of which comprise synchronizing-signal separating apparatus designed to respond to synchronizing signals having individual critical wave form characteristics of different types, a television transmitter synchronizing-signal generator including means for developing line-synchronizing impulses of predetermined amplitude, each having an edge of a predetermined slope, means for developing field-synchronizing impulses each having a different amplitude from said line-synchronizing impulses and having an edge corresponding to said edges of said line-synchronizing impulses of a predetermined different slope, and means for combining said line-synchronizing and field-synchronizing impulses with like polarity to develop and transmit a composite synchronizing signal to synchronize all of said certain receivers.

11. A television broadcasting system comprising, a plurality of receivers, certain of which comprise synchronizing-signal separating apparatus designed to respond to synchronizing signals having individual critical wave form characteristics of different types, a television transmitter synchronizing-signal generator including means for developing line-synchronizing impulses of predetermined duration and amplitude, each having an edge of a predetermined slope, means for developing field-synchronizing impulses, each having a different duration and amplitude from said line-synchronizing impulses and having an edge corresponding to said edges of said line-synchronizing impulses of a pre-

terminated different slope, and means for combining said line-synchronizing and field-synchronizing impulses with like polarity to develop and transmit a composite synchronizing signal to synchronize all of said certain receivers.

12. A television broadcasting system comprising, a plurality of receivers, certain of which comprise synchronizing-signal separating apparatus designed to respond to synchronizing signals having individual critical wave form characteristics of different types, a television transmitter synchronizing-signal generator including means for developing line-synchronizing impulses of a first predetermined frequency and duration, each having an edge of a predetermined slope, means for developing field-synchronizing impulses of double said predetermined frequency and of durations different from those of said

line-synchronizing impulses, each having an edge corresponding to said edges of said line-synchronizing impulses and of a predetermined different slope, means for developing alternate impulses at said predetermined frequency similar in duration 5 to said line-synchronizing impulses, means for combining said alternate impulses and said line-synchronizing impulses during predetermined periods occurring at a predetermined field-cancelling frequency, and means for combining said 10 field-synchronizing impulses with said line-synchronizing and alternate impulses during predetermined periods occurring during, but of less duration than, said first periods and for transmitting the resultant signal to synchronize said 15 certain receivers.
